AUTOMOBILE LOAD COVER FOR PICKUP TRUCKS

Lawrence Kroll, 201 N. Custer,
Weatherford, Okla. 73096

Filed Sept. 14, 1967, Ser. No. 8,594

Term of patent 14 years

(Cl. D14—27)

FIG. 1

The broken lines of a pickup truck are for purposes of illustration only.

I claim:

The ornamental design for an automobile load cover for pickup trucks, as shown and described.
